CLAIM

The ornamental design for a paper dispenser, as shown and described.

DESCRIPTION

FIG. 1 is a top, front, and right side perspective view of a paper dispenser showing my new design;

FIG. 2 is a front elevation view thereof;

FIG. 3 is a right side elevation view thereof;

FIG. 4 is a top plan view thereof;

FIG. 5 is a bottom plan view thereof;

FIG. 6 is a right side elevation view thereof; and,

FIG. 7 is a rear elevational view thereof.

The broken line disclosure is understood to represent portions of the article in which the claimed design is embodied, but which form no part of the claimed design.
